REEL

Arthur Alfred Bureau, Chicago, Ill., assignor to
 Western Electric Company, Incorporated, New
 York, N. Y., a corporation of New York

Application June 26, 1928, Serial No. 288,380
 Renewed October 26, 1933

3 Claims. (Cl. 242—77)

This invention relates to reels, and more particularly to metallic reels for holding cable or other heavy material susceptible to being wound thereon.

5 The primary object of the invention is to provide a reel which is of simple and rigid construction, economical to manufacture and durable in service.

In accordance with the above object, the invention contemplates a reel comprising a drum having angle members secured at each end thereof for securing the heads thereto. In the preferred embodiment of the invention, an angle member formed into a ring is welded to the drum 10 at each end thereof and is secured to the heads by means of bolts or the like.

A clear understanding of the inventive structure may be had from the following description taken in connection with the accompanying drawing, wherein,

Fig. 1 is an end view of a reel embodying the features of the invention;

Fig. 2 is an enlarged sectional view of the reel taken on line 2—2 of Fig. 1, showing a supply of cable wound thereon;

Fig. 3 is a perspective view of the drum with a ring-shaped angle member secured at each end thereof in accordance with the preferred form of the invention, and,

Fig. 4 is an enlarged fragmentary sectional view showing the preferred method of securing the angle member to the drum and heads of the reel.

Referring now to the drawing wherein like numerals designate similar parts throughout the several views, a steel drum 5 is secured between two heads 6 in the manner shown by Fig. 2, the drum itself and co-operating flanges being shown in Fig. 3, and the details for fastening the drum to a head are disclosed by Fig. 4.

40 The heads 6 are preferably made of sheet steel with alternate short and long radial ribs 7 and 8 (Fig. 1) pressed therein for the purpose of stiffening the metal. The steel drum 5 is secured to the heads by means of circular angle members 9 which are preferably welded to the inner surfaces of the drum adjacent the ends thereof and connected to the heads by bolts.

The securing of the angles to the drum provides a convenient way of flanging the ends and at the same time strengthens the drum. The angles may consist of a number of similar sections, but are preferably shaped into rings which are welded to the periphery of each end of the drum. The welding is preferably done on two edges 10 and 11 of the angle, as illustrated in Fig. 4, in order

to establish a firm bond, and the welding may be accomplished by any of the methods well known to the art, such as the metallic arc process.

The central portions of the heads are held in a fixed spaced relationship by a cylindrical spacer 15 and hubs secured thereto. A cylindrical spacer 15 extends between apertures 16 central of the heads 6 and has secured to the ends thereof hubs 17 abutting against the central outer surfaces of the heads 6, the hubs being held in this position by long bolts 18 extending therebetween.

The circumferential portions of the heads may be provided with outwardly turned flanges 22 braced by plates 23, and lags 24 may be secured to the flanges 22 by bands 25 for retaining material 26 wound on the reel.

In assembling the reel the drum with the ring-shaped angles 9 welded to the ends thereof in the manner described is placed between the heads 6 with apertures 30 in the flange portion of the angle 9 in alignment with corresponding apertures in the heads 6, and bolts 31 and 32 are inserted within said apertures and tightened for securing the heads to the angle flanges of the drum. In order to permit the installation of the bolts 31 hand holes 33 are provided in the heads adjacent to the inner surface of the drum so that a workman's hand may be inserted therein. The spacer 15 is inserted within the central apertures 16, the hubs 17 are placed within the spacer, and bolts 18 are inserted within apertures in the hubs and tightened to secure the central portions of the heads in fixed relationship.

After the joining of the spacer and drum to the heads as described, the material 26 may be wound on the reel and the lags 24 secured thereto for retaining the wound material in place. An aperture 34 may be provided in one head, and adjacent to the outer surface of the drum for the purpose of receiving and securing the inner end of the material.

The welding of the ring-shaped angles to the ends of the drum for providing flanges therefor affords a simple and efficient means for securing the drum to the heads, but it is of course to be understood that the invention is not limited to the specific embodiment described, but is restricted only by the scope of the appended claims.

What is claimed is:

1. A cable reel comprising spaced metallic heads having axial apertures therein, a metallic drum positioned between the heads, a pair of continuous annular supporting members secured to a surface of the drum adjacent its ends and secured directly to the heads, and a tubular hub member

extending between said apertures and having outwardly extending flanges secured to the heads.

2. A cable reel comprising spaced metallic heads having axial apertures therein, a metallic drum positioned between the heads, continuous annular supporting members secured to a surface of the drum adjacent its ends and bolted to the heads, a tubular hub member extending between said apertures and terminating in outwardly turned flanges contacting with the heads, and through-bolts securing said flanges to the heads.

3. A cable reel comprising spaced heads having axial apertures therein, a drum positioned between the heads, a pair of annular supporting members secured to a surface of the drum adjacent its ends and secured directly to the heads, and a tubular hub member extending between said apertures and having outwardly extending flanges secured to the heads.
